UNITED STATES PATENT OFFICE.

HERMAN H. LOUIS, OF NEWBURG HAMLET, OHIO, ASSIGNOR OF
TWO-THIRDS TO H. M. FENTON AND JOSEPH P. HAMILTON,
OF CLEVELAND, OHIO.

SWITCH-LOCK.

SPECIFICATION forming part of Letters Patent No. 734,723, dated July 28, 1903.

Application filed February 13, 1902. Serial No. 93,836. (No model.)

To all whom it may concern:

Be it known that I, HERMAN H. LOUIS, a citizen of the United States, and a resident of Newburg Hamlet, county of Cuyahoga, and 5 State of Ohio, have invented a new and useful Improvement in Switch-Locks, of which the following is a specification, the principle of the invention being herein explained and the best mode in which I have contemplated applying that principle, so as to distinguish it 10 from other inventions.

My invention relates to street - railway switches which are manually operated, its object being to lock the switch-point of the 15 switch in either of its two extreme or operative positions, whereby its accidental displacement during the passage of a car over it is prevented. In the double-truck cars at present used the switch-point after having been 20 shifted to the desired position by the motor-man frequently becomes displaced by the rear wheels of the front truck, and thereby causes the rear truck to take the wrong track. Such accident is exceedingly troublesome, and long 25 delays on car-lines are experienced as a result, it being frequently found to be exceedingly difficult to back the car, since such rear truck in so deviating becomes derailed.

Said invention consists of means hereinafter fully described, and particularly set forth 30 in the claims.

The annexed drawings and the following description set forth in detail certain mechanism embodying the invention, such disclosed means constituting but one of various 35 mechanical forms in which the principle of the invention may be used.

In said annexed drawings, Figure I represents a plan view of a device embodying my 40 invention, showing also a portion of a car-track adjacent to the switch-point. Fig. II represents a vertical longitudinal section of the device, taken upon the line 2 2, Fig. I, showing such track portion also in section.

The switch-point A is pivoted at its end, so 45 as to be oscillatory, its axis of oscillation being coincident with the axis of a downwardly-extending shaft B, secured to the point and passing through a supporting-plate C, forming 50 a part of the rails or switch secured there-

to. The lower end of said shaft passes through the walls of a metal protecting-easing D and has secured thereto one end of an arm E, whose other end is provided with an antifriction-roller e. Said arm, it is seen, is hence 55 capable of oscillation with the switch-point A and shaft B. In the path of said roller are two oppositely-inclined surfaces f f, formed upon the end of a spring-actuated plunger F, one of said surfaces being kept constantly in 60 contact with said roller by the helical spring F', located in a barrel F² and confined therein by a plate F³, which is held therein by a screw F⁴, engaging a thread formed in or otherwise secured to the casting F⁵, of which the barrel 65 forms a part. It is seen that by means of the screw the tension of the spring may be varied. Said casting is, as shown, located within the casing D and is removably secured thereto in by means of four set-screws f' f', which 70 pass through flanges f² of the casting and are caused to engage the adjacent sides of the casing. The plunger being in contact with and pressing against the roller holds the arm and shaft securely at one end of their oscillatory stroke and the switch-point in its corresponding extreme position or end of its oscillatory stroke. When it is desired to change the position of the point, it is manually thrown 75 over toward the opposite side. Such action 80 changes the position of the arm, causes the roller to travel across the inclined surface with which it is in contact, and thereby causes the plunger to yield until the roller passes over to the opposite inclined surface. On so 85 reaching such surface the plunger actuates the arm to throw the switch-point entirely over and locks it in such position.

It will be seen that by using the construction above described the entire mechanism 90 is inclosed in a protecting-covering, thereby preventing interference with its proper operation from external causes. The point of entrance of the shaft B into the casing D is made so as to cause said shaft to fit snugly, 95 thereby preventing the entrance of dirt and dust into such casing. By making the axis of this shaft coincident with the axis of oscillation of the switch-point it is seen that the necessity for the use of slots is entirely dis- 100

- pensed with, and the bearing of the shaft in the plate C may be made to fit snugly, so that it is seen that the possibility of interference with the correct operation of the device is reduced to a minimum. Such construction further permits all the mechanism to be placed below the surface of the road-bed, thereby entirely removing it as a cause of obstruction to vehicles passing over such bed.
- 10 Other modes of applying the principle of my invention may be employed instead of the one explained, change being made as regards the mechanism herein disclosed provided the means stated by any one of the following
- 15 claims or the equivalent of such stated means be employed.
- I therefore particularly point out and distinctly claim as my invention—
1. The combination of an oscillatory switch-
- 20 point provided with a shaft coaxial with its axis of oscillation, a laterally-extending arm

and a spring-actuated plunger having oppositely-inclined surfaces, the latter lying in the oscillatory path of the end of said arm.

2. The combination of an oscillatory switch-point provided with a shaft coaxial with its axis of oscillation, a laterally-extending arm secured to said shaft, a casing, and means in said casing for engaging and securing said arm at the ends of its path of oscillation, said means consisting of a casting adjustably and removably securable in said casing, and a spring-actuated plunger having oppositely-inclined bearing-surfaces engaging said arm to hold same. 25 30

Signed by me this 11th day of February, 35
1902.

HERMAN H. LOUIS.
